UNITED STATES PATENT OFFICE

157,791

COCKTAIL TABLE OR THE LIKE

Herbert Ritts, Los Angeles, Calif.

Application February 26, 1949, Serial No. 1,113

Term of patent 14 years

(Cl. D33—14)

To all whom it may concern:

Be it known that I, Herbert Ritts, a citizen of the United States of America, residing at Los Angeles, in the county of Los Angeles, State of California, have invented a new, original, and ornamental Design for a Cocktail Table or the like, of which the following is a specification, reference being had to the accompanying drawing, forming a part thereof.

I claim:

The ornamental design for a cocktail table or the like, substantially as shown.

HERBERT RITTS.
